CLAIM

The ornamental design for a wallet, as shown and described.

DESCRIPTION

FIG. 1 is a front perspective view of a wallet, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The dash-dash broken lines in the drawings show portions of the wallet that form no part of the claimed design.

The dot-dash-dot broken lines representing stitching are not part of the claimed design.

The dot-long dash-short dash-dot broken lines encircling the enlarged views are for annotative purposes only and form no part of the claim thereof.
